UNITED STATES PATENT OFFICE.

ROBERT H. RICHARDS, OF BOSTON, MASSACHUSETTS.

CONCENTRATING-TABLE.

1,197,398.

Specification of Letters Patent. Patented Sept. 5, 1916.

Application filed May 6, 1913. Serial No. 765,915.

To all whom it may concern:

Be it known that I, ROBERT H. RICHARDS, a citizen of the United States, residing at Boston, in the county of Suffolk and State of Massachusetts, have invented certain new and useful Improvements in Concentrating-Tables, of which the following is a specification.

This invention pertains to concentrating tables of the Wilfley type, and more especially to those which are longitudinally reciprocated.

The purpose of the invention is to increase the capacity of the table and insure closer and better separation, or to state it in another way, to enable a table of reduced size, involving smaller expenditure of power and less water consumption, to perform the work of larger tables of prior construction, and to effect a cleaner separation of product.

Five features contribute to the improved results, by reason of their presence and coöperation in the table. These are: First. The use of the Wilfley diagonal of advancing terminals. Second. The making of the top surface of the table in a single or common plane, the riffles or channels being sunk below such surface, with the tops of the separating ribs, cleats or walls in plane with the smooth portion of the table surface. Third. Forming the concentrate discharge end of the table oblique to its longitudinal axis. Fourth. Causing the diagonal terminal line of the riffles, or the dividing line between the riffled and the smooth portions of the table, to extend to a point on the concentrate discharge end of the table somewhat above the lower corner or angle of said table. Fifth. Forming at the concentrate discharge end of the table a series of corrugations, grooves or channels, extending in the direction of the length of the table, and parallel to the riffles but inclining downward. Some of these features are old *per se*, but so far as I am aware, they have not hitherto been combined in one structure. When so combined, they mutually affect one another, and contribute to the unitary result,—the perfect concentration of minerals, and the complete and close separation of concentrates from quartz, sand and other matters.

The invention is illustrated in the accompanying drawings, wherein:

Figure 1 is a top plan view of the table;

Fig. 2 is a perspective view designed to show better the corrugated or grooved concentrate discharge end of the table, and the action of the grooves or corrugations in securing perfect separation and delivery of products. Fig. 3, a longitudinal section on the line 3—3 of Fig. 1; Fig. 4, a transverse section through the table proper showing riffle grooves cut into the table surface; Fig. 5, a similar section showing tapered strips or riffle cleats formed separate from and secured to the table, this being a modified construction.

In these drawings, 1 indicates the table proper, which may be constructed of any suitable material, and which may advantageously be of wood covered with linoleum, because this substance has a surface admirably suited to the purpose, its use being particularly satisfactory on the smooth or unriffled portion 2 of the table. The riffles will be seen from the drawing to have the Wilfley diagonal of advancing terminals, by which is meant that the ends of the riffle cleats in series, beginning at the upper end or feed side of the table, are advanced along an oblique line toward the concentrate-discharge end of the table and toward the tailing side; that is to say, the end of each lower riffle extends a little beyond the one above it toward the concentrate discharge end, making thereby an oblique line of advancing terminals.

The entire upper surface of the table is in common plane, that is to say, the smooth or unriffled surface 2 and the upper surfaces of the ribs or riffle cleats 3 which separate the riffles or grooves 4, lie in one and the same plane, while said riffle cleats are three-eighths of an inch more or less deep at the lower corner of the mechanism end of the table, and become progressively shallower until they disappear at the oblique line of meeting with the smooth portion 2 of the table surface, as best indicated in Fig. 3. The riffle cleats are all of about the same taper, and the thick ends, that is, the ends toward the mechanism end of the table, will therefore be of a thickness or height diminishing from the lower or tailing side to the upper or feed side of the table.

The riffles may be formed by grooving or channeling the surface of the table, with or without linoleum, as in Fig. 4, or by making the surface of the table initially of two

planes, one at a quite obtuse angle to the other, and thereafter securing to the depressed plane separate riffle cleats or strips 3^a, as illustrated in Fig. 5. The taper of 5 the riffle cleats is just sufficient to bring their top surfaces up to the plane of the smooth or unriffled surface. This latter construction will be found convenient where it is desired to employ linoleum on the surface of the 10 table, since the entire surface may be covered with a layer 5 of linoleum, as seen in Fig. 5, preparatory to securing upon the depressed plane of the table the tapered ribs or riffle cleats 3^a. Still another way of 15 accomplishing the result, which gives virtually a one-plane table and admirable results in practice, is to make the table with a single plane surface covered with linoleum, and tack on it thin riffle cleats $\frac{1}{16}$ of an inch 20 thick, more or less, and of uniform thickness throughout their entire length, using the oblique line of ends or not as preferred.

As shown in Fig. 1, the concentrate-discharge end of the table is made oblique to 25 the longitudinal axis of the table, while the mechanism end thereof may be rectangular, the lower or tailing-discharge side of the table being under those conditions the shorter side. While I prefer this form of 30 table, my invention is applicable to other forms, with which all or many of its advantages are secured. I do not therefore, limit myself to this form of table except as specifically stated in the claims.

35 It has hitherto been customary to make the diagonal terminal line of the riffles extend from a point on the upper or feed side of the table, and at a relatively short distance from the mechanism end of the table, 40 to the lower corner of the table at the concentrate-discharge end. I prefer, however, to extend a limited number of the riffles at the lower or tailing side of the table, all the way from the mechanism end to the 45 concentrate-discharge end, as indicated in Fig. 1; hence the oblique line separating the smooth surface 2 of the table from the riffled surface may begin at about the usual point on the upper or feed side of the table and 50 extend to a point on the concentrate-discharge end of the table somewhat back of or above the tailing side and the lower corner or angle.

55 At the concentrate-discharge end of the table I form a series of grooves, channels, or corrugations 6, which may be of V-shape or other suitable cross section, said corrugations extending in the direction of the axis of the table and in the line of reciprocation, and in plan parallel to the riffle cleats but inclining downward as indicated in Figs. 2 and 3. The purpose of these corrugations, grooves or channels 6 is to insure 60 delivery of each separate product into its proper receptacle, and to overcome the diffi-

culty inherent in many tables of this sort now in use, of having particles of one class carried out of their proper path, and delivered into the receptacle designed for another class, by reason of the cross flow of the wash 70 water at the end of the table and the capillarity or creeping of the particles on the end or under the end, causing delivery of such particles away from their own box or bin into a neighboring box intended for another 75 product.

The improvement obtained by bringing the diagonal line of riffle tips up some inches above the lower corner of the table, is that the line of the dividing partition between 80 the receptacle belonging to one product and that belonging to another, is coincident with the direction or swing of the particles, and hence the particles as they swing off the table drop into the box for which they are 85 intended, while if this dividing line is put along the tailing-discharge side, the particles as they swing off the table move transverse to the direction of the dividing partitions and swing now in and now out of their 90 own box. In the use of tables of prior construction, it is found that after the grains have been properly separated and brought thus separated to the concentrate end of the 95 table, the wash water flowing across the table and discharging from its end during the backward throw of the table, carries with it in a direction transverse or oblique to the line of reciprocation, particles lying 100 in its path or falling from the table, and deflects them from their proper course, frequently delivering them from one to several inches to one side of the point at which they should be delivered. By reason of the corrugations, grooves or channels 6, the 105 grains or particles are firmly held against lateral movement while traversing the inclined edge at the concentrate-discharge end of the table, and they are consequently caused to move only in the direction of the 110 reciprocation of the table; hence by employing thin walls of sheet metal or other suitable material, to mark the boundaries between the different receptacles or the chutes leading thereto, I am enabled to make 115 a sharp and clean line of division between the several products.

In Figs. 1 and 2 of the drawings I have represented the middling as being delivered from the lower angle of the smooth surfaced 120 section 2 of the table to a receptacle, the receiving mouth of which is separated by vertical walls or dividers 7 and 8 of sheet metal, wood or other material, from the chutes 9 and 10 over which the other products reaching the end of the table are 125 delivered to their appropriate receptacles. Thus, assuming that middling is to be saved and separated from tailing and concentrate, the concentrate would fall upon the inclined 130

chute or surface 9, the quartz upon the oppositely-inclined chute or surface 10, while the middling falling between the upright walls or dividers 7 and 8, would enter the receptacle 11. The walls or dividers 7 and 8 are made adjustable toward and from each other, and are set in accordance with the width of the band of concentrate or middling as the same reaches the discharge end 10 of the table. This width varies according to the class of materials treated, and the walls 7 and 8 are adjusted as soon as the band becomes well established, since the width remains practically constant thereafter if the 15 feed to the table is steady. The walls being thus set, and the grains or particles being guided in and by the corrugations or grooves, each class will fall into its proper division or receptacle. These dividers for 20 making separation between the products may be made in other ways besides those indicated, and the number of them may be increased or diminished.

12 indicates a water pipe extending 25 lengthwise of the table just above its edge on the high or feed side, which pipe is provided with a series of taps or cocks 13, or it may be a trough with holes for water and suitable water checks, and 14 is a feed hopper, spout, or chute on the feed side of the 30 table, and reaching from the mechanism end for a suitable distance toward the concentrate discharge end.

In the operation of the machine the pulp 35 is delivered by the chute or hopper 14 to the narrower upper portion of the riffled surface of the table, together with a suitable quantity of water, and the taps 13 are, either preliminarily or as the work progresses, 40 opened to deliver suitable quantities of water along the upper or feed side of the table. The action of the table is as follows: The jerking action produced by the mechanism tends to advance the grains of sand 45 toward the concentrate end. This vibration tends also to stratify the sands in such a way that the heavier grains are underneath, while the lighter grains are above. The transverse flow of water tends to carry 50 the sands down the slope toward the tailing side, which movement is retarded by the riffle grooves, but since the agitation due to the mechanism has stratified the sands within the riffle grooves, it is only the 55 top layer of lighter waste material that is carried down toward the tailing side. The heavier portion in the layer beneath is constantly advancing toward the terminals of the riffle grooves, and finally delivered out 60 on to the smooth or unriffled portion. The special use of the advancing terminals is to give to the doubtful grains, by which I mean the grains that are not quite heavy enough to 65 be concentrate nor light enough to be tailing, or the fine grains that have not quite

weight enough to be sure to get into the concentrate band at the first opportunity,— an oft-repeated chance of being accepted as concentrate or being rejected as tailing, according to whether they are finally heavy 70 enough to attain the advancement into the concentrate band or light enough to be thrown into the tailing band. By this progressive travel over and through the riffles the different substances are gradually separated, the gangue flowing off at the lower 75 side of the table, the concentrate arranging itself in a band of increasing width along the lower side of the unriffled portion of the table, and middling, or matter heavier than 80 the quartz but lighter than the concentrate, distributing itself in a band between the concentrate and the tailing, usually along and slightly below the terminals of the riffles.

The one plane construction, which is one 85 of the features of this invention, produces the effect of widening out the bands of concentrate, middling and tailing to a very considerable extent. This widening is due to 90 the fact that water and water carrying sand will spread out to greater width if flowing upon a plane surface, than they will if they are flowing in a trough made up of two planes sloping toward one another near their 95 line of intersection, be the angle of convergence of the two planes ever so slight in its variance from the straight line. The practical working of a one plane table as compared with a two plane table is that the 100 widening out of the bands, due to the one plane table, occurs at a very considerably wider angle than happens on the two plane table, thus effecting sufficient separation of the concentrate from the tailing by traveling 105 a shorter distance than would be required on the two plane table. Indeed, it frequently happens on the two plane table, that the bands travel along on parallel roads without widening at all after the first three or four 110 feet have been passed. This arriving at sufficient separation in the shorter distance, enables one to use a much smaller table than would be required where the two plane table is used.

The quantity of water employed, and the power necessary to operate the smaller and lighter table, are proportionately less, while owing primarily to the corrugated or grooved discharge end of the table, and to 115 making the division line between the concentrate and the tailing on the end of the table instead of at the lower corner or on the lower edge thereof, the separation is cleaner and closer than has heretofore been 120 found possible.

The corrugations, grooves or channels at the concentrate-discharge end of the table may be formed in the body of the table 125 itself, or may be made of metal, cast, bent, 130

or otherwise fashioned into shape, as shall be found convenient in practice.

Briefly recapitulating the features of my table and their purpose and effect, the riffles 5 serve to retain the heavy under layer of concentrate while the lighter quartz resting above the concentrate is floated off over the cleats or riffle walls and down the table toward the tailing side, as heretofore. With 10 a table having its entire upper surface in common plane and the riffles wholly below such plane, there is a greater widening of the bands formed by the different materials than is the case where the linoleum surface 15 is all one plane with taper riffle cleats tacked on, which widening is the purpose for which tables of this class are designed.

By carrying some of the riffles at the lower side of the table entirely to the delivery or concentrate-discharge end, and having the lowermost point of the smooth surface 2 of the table terminate somewhat above the lower side of the table, say ten inches more or less, the division between 25 middling and quartz, or other relatively light product, is made on the end of the table, and with the aid of the corrugations on the end edge of the table, each class of material or each product of the separation, 30 is caused to leave the end of the table in a right-line in the direction of the reciprocating movement, unaffected by the throw due to the reciprocation. As a result the dividers for separating these products can be 35 so lined up that the one product always remains on the one side, and the other product always on the other side of the dividing partition, as should be done. On the other hand, if the diagonal line of advancing terminals comes out at the lower corner of the 40 concentrate-discharge end, bringing the dividing line between the middling and tailing on the tailing side of the table, then the middling product and tailing product are 45 thrown from the table now one way and now the other with reference to the dividing partition between the two products, and, according to the phase of the movement of the mechanism, at one instant middling is 50 thrown into tailing, and at another instant tailing is thrown into middling.

By making the delivery end of the table oblique, and having the wash water come on at the upper side of the table, or by other 55 appropriate construction, a wetted edge is assured, and a proper delivery of the products without any heaping of dry banks, and without boring or displacement such as produced by wash jets arranged merely to keep 60 the edge wet.

It will be seen from the foregoing description that the single plane construction tends to produce wider bands of the different products or classes of material, since there is not present the valley or trough-like

table surface incident to the employment of tapering cleats or ribs secured upon a previously plane surface. This broadening of the bands, which of course increases toward the discharge end of the table, makes easier the division of the products and their delivery into separate receptacles, which is further facilitated by making the division between the middling and the tailing on the end instead of at the side or corner of the table. Finally, the corrugations serve to prevent the remingling of products once separated, yet allow a free and adequate flow of water over the end of the table to maintain a wetted edge, which is finally insured by obliquity of the end.

Having thus described my invention, what I claim is:—

1. The combination of a laterally inclined, longitudinally shaking concentrating table adapted to deliver the concentrated product over the end edge thereof; guiding means on the discharge end of said table, extending substantially the entire depth of said end edge to guide the concentrated product during discharge, and a divider structure for receiving material discharged from said guiding means and for maintaining the classification thereof.

2. The combination of a laterally inclined, longitudinally shaking concentrating table having an oblique concentrate discharge end and a top surface adapted under the shaking action to propel the lighter and heavier particles in divergent paths, the heavier particles being discharged solely over the edge of said oblique end; and guiding means on said oblique end extending substantially the entire depth of said end edge and in the direction of shake of said table.

3. The combination of a laterally inclined longitudinally shaking one-plane concentrating table having an oblique concentrate discharge end and having longitudinally extending riffle grooves adapted to propel the heavier particles in a relatively wide band all to the oblique end and to propel the lighter particles in a divergent path partly to the end and partly to the low side of said table; and guiding means on said oblique end extending in the direction of shake of said table and substantially the entire depth of the edge of said oblique end, to guide discharging particles.

4. The combination of a longitudinally shaking concentrating table adapted to propel the heavier and lighter materials in divergent paths toward one end of said table; a plurality of guide ribs or flanges on said end of the table and extending in the general direction of shake of the table for guiding material discharging over said end; and a divider structure for receiving said discharging material and maintaining the classification thereof.

5. The combination of a longitudinally shaking concentrating table having an oblique concentrate discharge end, and adapted to propel the heavier materials and 5 at least part of the lighter materials in divergent paths to said oblique discharge end; and a plurality of guide ribs or flanges mounted on the discharge end of said table and extending in the general direction of 10 shake thereof.

6. The combination of a shaking concentrating table adapted to propel the lighter and heavier materials in divergent paths,

and having the discharge end beveled to form a steeply inclined discharging surface; 15 and a plurality of guide ribs or flanges on said discharging surface and extending in the general direction of shake of said table.

In testimony whereof I have signed my name to this specification in the presence 20 of two subscribing witnesses.
